United States Patent

Des. 236,012
Patented July 22, 1975

236,012

ANIMAL FEEDER OR THE LIKE

Beverley Crawford, 315 E. 65th St. 10021, and Genelle Jenkins, 107 E. 60th St. 10022, both of New York, N.Y.

Filed July 5, 1973, Ser. No. 376,895

Term of patent 14 years

Int. Cl. D30—03

U.S. Cl. D30—13

FIG.1

FIG.4

FIG. 1 is a perspective view of an animal feeder showing our new design;

FIG. 2 is a rear perspective view thereof;

FIG. 3 is a reduced scale exploded perspective view; and

FIG. 4 is a top plan view of the animal feeder with the cover removed.

We claim:

The ornamental design for an animal feeder or the like, substantially as shown and described.
